UNITED STATES PATENT OFFICE.

VICTOR MAPES, OF NEW YORK, N. Y., ASSIGNOR OF ONE-HALF TO
OAKLEIGH THORNE, OF MILLBROOK, NEW YORK.

DICE.

SPECIFICATION forming part of Letters Patent No. 645,112, dated March 13, 1900.

Application filed January 21, 1899. Serial No. 702,890. (No model.)

To all whom it may concern:

Be it known that I, VICTOR MAPES, a citizen of the United States, residing at New York city, in the borough of Manhattan, in the State 5 of New York, have invented certain new and useful Improvements in Dice, of which the following is a specification.

My invention relates to improvements in dice adapted for amusement; and the essential object of the invention is the production 10 of dice with which various games of cards may be played.

To this end the invention consists of a series of, preferably, five dice having thereon 15 the representation or designation of the fifty-two cards comprising a pack. The representations or designations are so disposed that one may be clearly disclosed at any position which the dice may take, and the dice are 20 therefore preferably provided with opposite facets on which the representations or designations are placed. The form for each die is a dodecahedron, and on four of the dice ten of the facets, and on the other one twelve of 25 the facets, may be occupied. This will leave four dice each with two unoccupied facets and one die with no unoccupied facet. In order to prevent the dice from disclosing an unoccupied or blank facet during the game, I provide 30 the same with a device or means for preventing the dice from resting with a blank facet uppermost. This may be accomplished by rounding the facet opposite each blank or 35 by providing each of said opposite facets with a stud or projection, as will be explained. The representations or designations of the 40 fifty-two cards are so placed on the dice as to enable different combinations to be secured. To effect this result, a duplication of a card 45 or its designation should not occur on any die, and the several suits should be divided between the dice as evenly as possible.

In order that my invention may be better understood, attention is directed to the accompanying drawings, forming a part of this 50 specification, and in which—

Figure 1 is a perspective view of a die embodying the invention; Fig. 2, a section thereof; Fig. 3, a section of a modification, and 55 Fig. 4 a diagrammatic view illustrating a convenient arrangement of the five dice.

In all the above views corresponding parts are represented by the same letters of reference.

A represents one of the dice made in the 55 form of a dodecahedron. These dice are made of any suitable material—such as wood, ivory or celluloid—and are imprinted with or carry the representations or designations of the cards in any desired way. As stated, a convenient arrangement is to place on four of the dice the designations or representations of ten cards and on one die of twelve cards. In order to prevent the unoccupied surfaces from being disclosed during the game, the facet opposite to each unoccupied surface may be rounded, as at *a*, Fig. 2, or be provided with a projection, such as *b*, Fig. 3, by either of which means the same result is secured. It will of course be understood that the exposed 65 side of the die is the horizontal or top side and that a blank side is prevented from being exposed, since the peculiar structure of the directly-opposite face is such as to prevent any blank side from appearing at the top. 70 The actual representations of the cards may be imprinted or affixed on the die-facets; but preferably the cards are designated by the more conventional methods, thus, as shown, the deuce of diamonds, which appears on the 75 exposed or upper face of the die, (illustrated in Fig. 1,) may be represented by the numeral 2, carried upon the representation of a diamond.

In Fig. 4 I illustrate a convenient arrangement for the five dice, the latter being designated A, B, C, D, and E, and wherein the cards are so arranged that duplicates in number do not occur on any die and the suits are distributed as evenly as possible. On A there 80 are ace, nine, and four of hearts, king, five, and three of spades, queen, seven, and two of diamonds, ten, eight, and six of clubs. On B there are ace, seven, and two of spades, king, eight, and three of hearts, queen and four of 85 clubs, jack and six of diamonds. On C there are ace, nine, and five of diamonds, king and three of clubs, jack, seven, and two of hearts, ten and six of spades. On D there are ace, five, and two of clubs, queen and six of hearts, 90 jack, nine, and four of spades, ten and eight of diamonds. On E there are king, four, and 95 100

three of diamonds, queen and eight of spades, jack, nine, and seven of clubs, ten and five of hearts. Other arrangements may be adopted; but that indicated is considered preferable.

5 Having now described my invention, what I claim as new, and desire to secure by Letters Patent, is—

An improved set of five dice for playing games, each being in the form of a dodecahedron carrying the representations and design-

nations of the fifty-two cards, and provided with means for preventing the exposure of a blank or unoccupied facet, substantially as set forth.

This specification signed and witnessed this 15
19th day of January, 1899.

VICTOR MAPES.
